United States Defensive Publication

[19] (H)

[11]

T102,402

Young

[43]

Nov. 2, 1982

[54] METHOD OF RECOVERING A
PHOTOGRAPHIC ADDENDUM FROM A
DISPERSION THEREOF

[52] U.S. Cl. 430/449; 430/377;
430/546

[76] Inventor: David J. Young, c/o Kodak Limited,
Hemel Hempstead, Hertfordshire,
England, HP1 1JU

[57] ABSTRACT

[21] Appl. No.: 373,193

A water-insoluble organic photographic addendum is recovered from a dispersion of a mixture thereof and an oil-former in an aqueous medium containing a hydrophilic colloid and a surface active agent by adding a selected oleophilic non-ionic surface active agent.

[22] Filed: Apr. 29, 1982

4 Claims, No Sheets Drawing,

[30] Foreign Application Priority Data

13 Pages Specification

Sep. 1, 1980 [GB] United Kingdom 8028150

The file of this unexamined application may be inspected and copies thereof may be purchased (849 O.G. 1221, Apr. 9, 1968).

[51] Int. Cl.³ G03C 1/40